CLAIM

The ornamental design for a dryer vent for half block foundation opening, as shown and described.

DESCRIPTION

FIG. 1 is a front perspective view of the dryer vent for half block foundation opening showing my new design;

FIG. 2 is a front elevational view thereof;

FIG. 3 is a rear elevational view thereof;

FIG. 4 is a bottom plan view thereof, the top plan view being a mirror image thereof; and,

FIG. 5 is a left side elevational view thereof, the opposite side being a mirror image thereof.
